CLAIM

U.S. PATENT DOCUMENTS

The ornamental design for an antiperspirant and/or deodorant product, as shown and described.

DESCRIPTION

D27,864 S	11/1897	Blackman
692,481 A	2/1902	Robinson
964,422 A	7/1910	Hood
1,669,016 A	5/1928	O'Neil
1,791,359 A	2/1931	Henriksen
2,101,540 A	12/1937	Gullich
2,165,420 A	7/1939	Siefert
2,174,779 A	10/1939	Delorme
2,613,185 A	10/1952	Marshall
2,980,083 A	1/1961	Bell
D201,229 S	5/1965	Burke
3,294,692 A	12/1966	Kelly et al.
3,479,429 A	11/1969	Morshauser et al.
4,120,948 A	10/1978	Shelton

FIG. 1 is a perspective view of an antiperspirant and/or deodorant product showing the new design;

FIG. 2 is a front elevation view of the antiperspirant and/or deodorant product, the rear elevation view being a mirror image thereof; and,

FIG. 3 is an end elevation view of the antiperspirant and/or deodorant product, the other side elevation view being a mirror image thereof.

The inner broken lines, which define outer boundaries of the claimed design, form no part thereof. The remaining broken lines are for illustrative purposes only and form no part of the claimed design.
